UNITED STATES PATENT OFFICE.

CHARLES MAGEE, OF BROOKLYN, NEW YORK, ASSIGNOR TO THE BIGELOW CARPET COMPANY, OF CLINTON, MASSACHUSETTS.

DESIGN FOR CARPET.

Specification forming part of Design No. **11,130**, dated April 1, 1879; application filed February 20, 1879.
[Term of patent 3½ years.]

To all whom it may concern:

Be it known that I, CHARLES MAGEE, of the city of Brooklyn, county of Kings, and State of New York, have invented a new and original Design for a Carpet, of which the following is a specification:

This invention relates to a new and original design for carpets, oil-cloths, and similar fabrics.

It consists in the new arrangement and ornamentation of figures constituting the design, hereinafter more fully pointed out.

The accompanying photographic illustration represents a face view of my new design.

The letter A represents the body of my newly-designed carpet. B is the border of the same. a represents a rectangular figure on the body A, having two rectangular projections at each corner, as shown. From the center of each of the sides of this figure project semicircular figures b b, which are indicated by dark semicircles in the photograph.

The figure a is situated within a larger irregular figure, d. This figure is composed of zigzag, curved, and straight lines, as shown. e f are two other irregular figures, in contact with the figure d. These figures are also made up of curved, straight, and zigzag lines.

g is a circular figure, partly overlapped by a rectangular figure, h, and partly inclosed by an approximately-annular figure, i, having a scalloped outline. The rectangle h is, by an oblique line, divided into two parts. It is, furthermore, ornamented by bell-shaped flowers l, a turret-like figure, m, and other ornaments.

The figure a is ornamented by differently-colored leaves; the figure d, by branches and flowers. The figures e and f contain rich floral

designs. The circular figure g contains ornamental scrolls, and the figure i is ornamented by lines and figures arranged to correspond with its outline. The border B contains, between two stripes, j k, substantial reproductions of the figures d and e. The stripe j contains a series of triangular projections, from the apex of each of which projects a turret-shaped figure with flowers at the sides, such flowers and turrets corresponding with the ornamentation of the figure h, heretofore described. The stripe k is composed of small geometrical patterns.

I claim—

1. The design for a carpet, consisting of the rectangle a and circular projections b, the rectangle a having two rectangular projections at each corner, substantially as shown.
2. The design for a carpet, consisting of the rectangular figure a and the irregular figure d, substantially as shown.
3. The design for a carpet, consisting of the irregular figures d and e, substantially as shown.
4. The design for a carpet, consisting of the irregular figures e and f, substantially as shown.
5. The design for a carpet, consisting of the circular figure g, rectangle h, and annular figure i, substantially as shown.
6. The design for a carpet, consisting of the bell-shaped flowers b and turret-shaped figures m, substantially as shown.
7. The design for a carpet, consisting of the figures a, d, e, f, g, h, and i, substantially as shown.

CHARLES MAGEE.
